Samuel Miller.

UNITED STATES PATENT OFFICE.

SAMUEL MILLER, OF WINCHESTER, OHIO.

IMPROVEMENT IN HARROWS.

Specification forming part of Letters Patent No. 31,731, dated March 19, 1861.

To all whom it may concern:

Be it known that I, SAMUEL MILLER, of Winchester, in the county of Preble and State of Ohio, have invented certain new and useful Improvements in Harrows; and I do hereby declare that the following is a full, clear, and exact description of the same, reference being had to the accompanying drawings, and to the letters of reference marked thereon, in which—

Figure 1 is a plan view of a fallow-ground harrow; Fig. 2, a plan of a joint-harrow; Fig. 3, plan of wide harrow; Fig. 4, plan of corn-harrow; Fig. 5, plan of cultivator, and Fig. 6 a side elevation of single plow.

The nature of my invention consists in the arrangements of those parts hereinafter set forth.

To enable others skilled in the art to make and use my invention, I will proceed to describe its construction and mode of alteration.

A represents the main or center piece; B B and C C, the wings or side pieces.

D D are pieces parallel to the main piece, and connect the wings B B and C C, as fully represented in Fig. 1.

E E are end pieces, which are secured to the main piece A by means of a wide staple, e, which cover the ends of E E, as fully shown.

Now, to change the fallow-ground harrow into a joint-harrow, I simply move the pieces D D closer to the main piece A, set the wings B B and C C farther back, and connect C C with one of the pieces E. To change it into a wide harrow, I remove the main piece entirely, bolt the ends of wings B B together, and connect them near the center with one of the wings C, as seen in Fig. 3. To change it into a single plow, take the main piece A, bolt one of the end pieces E to it, and secure the handles a a as seen in Fig. 6. Thus it will be observed that by constructing the various pieces as represented in the drawings the farmer may have without additional expense a variety of farming implements applicable to different purposes.

Having thus fully described my invention, what I claim, and desire to secure by Letters Patent, is—

The employment of pieces A, B, C, D, and E for operating conjointly, when constructed and arranged in the manner and for the purpose set forth.

SAMUEL MILLER.

Attest:

LEVI HOLTRY,
A. STIVER.
